LOCK

Norman B. Hurd, New Britain, Conn., assignor to
The American Hardware Corporation, New
Britain, Conn., a corporation of Connecticut

Application April 3, 1929, Serial No. 352,115

7 Claims. (Cl. 70—91)

My invention relates to a lock and more particularly to one of the type wherein the parts may be easily disassembled for changing the combination.

5 In locks on the doors of offices, apartment houses, and the like, wherein tenants often change, it is desirable to provide means for a quick change of the key combination of all locks. My invention is particularly adaptable to locks 10 of the type indicated, wherein the key combination is carried by the door knob, and the invention relates to certain details of construction whereby this combination may be readily removed and replaced by the same or a different combination.

15 It is the principal object of the invention to provide a lock of the character indicated having improved, simple means whereby by means of a special key the knob may be removed and the combination changed.

20 It is a further object to provide an improved lock of the character indicated, simple in construction, relatively cheap to manufacture, of sturdy construction, and serviceable in use.

25 In the drawing which shows, for illustrative purposes only, a preferred form of the invention—

Fig. 1 is a longitudinal central sectional view through a door knob and associated parts, and illustrating my invention, an ordinary pass key 30 being shown in place;

Fig. 2 is a view similar to Fig. 1, parts being separated, and a special key in place;

Fig. 3 is a perspective view of certain operative parts shown in Figs. 1 and 2 and relatively 35 separated.

In said drawing, 5 indicates a rotatable hollow spindle to be attached to a lock casing attached to the door. 5^a is a stationary sleeve-like support for said hollow spindle, said support being 40 part of the lock case or escutcheon plate, not shown. Since the latch or lock mechanism carried by the door may be of any preferred construction and forms no part of the present invention, no illustration thereof is made. 6 indicates a hollow knob and arranged for detachable 45 connection to the hollow spindle 5.

In the preferred form, the knob 6 carries a cylinder lock, the cylinder of which is non-rotatably held in the knob 6 as by means of the pin 50 casing 8 in engagement with the walls of a slot of corresponding shape in the rear of the door knob, as will be clear from Fig. 3. The lock casing 7, when parts are disassembled, is readily removable by drawing the same rearwardly out of the knob. In the preferred form, the rear of the

knob is provided with a threaded lug or projection 9, and a correspondingly threaded member, which I term a shank member or cover 10, is threaded onto the projection 9. The part 10 functions to hold the lock casing 7 in place. In order to prevent unscrewing and separation of the two parts 6 and 10 of the knob, I may employ a cover plate or ring member 11 carrying one or more pins 12 to pass through correspondingly spaced apertures 13—13 in a flange 14 on the part 10 and into correspondingly spaced apertures 15—15 in the rear face of the part 6. The member 10 is provided with means for engagement with the hollow spindle 5 and in the form shown I employ at the rear end of member 10 rearwardly extending spaced apart circumferential lugs 16—16 between which forwardly extending lugs 17—17 on the hollow spindle 5 may fit so as to couple the knob to the spindle 5 for rotation. The parts 5 and 10 are held together against relative axial 20 separation by a key actuated means to be described.

In the form shown, the cylinder 7 contains a plug 20 having usual pin tumblers 21 which are adapted to be actuated by an ordinary pass key 22. It will be noted particularly in Fig. 1 that the last tumbler 23 is not engaged by the pass key 22. The plug 20 in the preferred form shown carries a sleeve 24 which is normally locked to the casing 7 by means of the driver 25 as will also be clear from Fig. 1. The sleeve 24 extends rearwardly and carries one or more circumferential lugs 26. The parts 5—10 are provided with complementary abutment surfaces 28—28 so that when said parts are moved into longitudinal engagement 30 with each other as shown in Fig. 1 the lugs 26 may engage wholly or partially between the complementary abutment surfaces 28—28 so as to lock the said members 5—10 and associated parts against longitudinal separation. The key plug 7 or a continuation thereof carries a spindle 30 for unlimited rotation by key 22 for actuating the latch or lock mechanism (not shown).

In Fig. 1, parts are shown in the normal position, that is, with the members locked together. When it is desired to separate the parts so as to permit removal of the lock casing 7 to repair or change the combination, a special key 31, in this case longer than the pass key 22, is inserted into the plug as in Fig. 2, and this key 31 is so bitted as to set all of the ordinary tumblers as shown in Fig. 1 and also so as to raise the last tumbler 23 to such position that the sleeve 24 will be locked to the plug 20. By now turning the plug 20 by means of the special key 31, the locking lugs 26—26 may 55

be turned into the position shown in Fig. 2 and freed from the abutment surfaces 28-28 on the shank member 5. The knob 6 and the parts associated therewith as shown in Fig. 2 may then 5 be drawn outwardly, that is, toward the left, and thereafter the knob may be opened up to permit changing the combination. This is effected by first removing the cover plate 11 and withdrawing the locking pins 12-12, after which 10 the cover 10 may be unscrewed from the knob part 9 so that the cylinder lock may be withdrawn and a new lock combination made or substituted. Under normal conditions the part 24 and spindle 30 may partake of the limited rotation of the 15 knob at any time but this limited rotation is not sufficient to cause disengagement of the parts so that the knob may be withdrawn from the hollow spindle 5 nor need it be sufficient to cause spindle 30 to operate the part (not shown) designed to 20 be operated thereby.

While the invention has been disclosed in considerable detail and one specific embodiment thereof illustrated, it is to be understood that various changes in matters of detail may be made 25 within the scope of the invention as defined in the appended claims.

I claim:

1. In a lock, a knob, a lock casing in said knob, a shank member detachably connected to said knob, a second shank member for coaction with 30 said first mentioned shank member, said shank members having interengaging parts for preventing relative rotation therebetween, said shank members having abutment surfaces thereon, a 35 plug carried by said lock casing, and key actuated means rotatable with said plug and having means thereon for engagement with said abutment surfaces for preventing axial displacement of said shank members.
2. In a lock, a knob member formed in two 40 parts, lock mechanism secured between said knob parts, a member to be secured to a door, and means operable by a part of said lock mechanism for securing said member and one of said knob 45 parts together.

3. In a lock, a knob, lock mechanism within said knob, a member detachably secured to said knob for holding said lock mechanism in place, a member to be carried by a door, and means operable by a part of said lock mechanism for holding said two members together. 5

4. In a lock, a knob formed in two parts, means including a retaining member movable axially relatively to said knob for holding said knob parts together, lock mechanism within said knob, a 10 member to be secured to a door, and means operable by a part of said lock mechanism for securing said knob to said member to be secured to a door and preventing axial movement of said retaining member. 15

5. In a lock, a knob, lock mechanism carried by said knob, means for retaining said lock mechanism in said knob and including a retaining member movable axially of said knob into retaining and non-retaining position, an element 20 to be secured to a door, and means operable by a part of said lock mechanism for holding said knob to said element and preventing axial movement of said retaining member. 25

6. In a lock, a knob, lock mechanism within 30 said knob, retaining means for securing said lock mechanism in said knob, a member to be secured to a door, and means operable by a part of said lock mechanism for securing said knob to said member and holding said retaining means in place. 35

7. In a lock, a knob member, a shank member 40 removably secured to said knob member, a lock mechanism between said knob and shank members, a shank member to be carried by a door, said shank members having axially engageable keying means for holding said shank members against relative rotation, said lock mechanism including a plug part having means for locking said shank members against axial separation, and a second plug part rotatable relatively to said 45 first mentioned plug part for the purpose described. 45

NORMAN B. HURD.
